UNITED STATES PATENT OFFICE.

FRANCIS H. WEEKS, OF NEW YORK, N. Y.

HOISTING BUCKET.

Application filed August 20, 1925. Serial No. 51,360.

To all whom it may concern:

Be it known that I, FRANCIS H. WEEKS, a citizen of the United States, and a resident of the city of New York, county of Bronx, 5 and State of New York, have invented an Improvement in Hoisting Buckets, of which the following is a specification.

My invention relates to improvements in hoisting buckets, and more particularly to 10 means for converting a hoisting bucket, such for example as a clam shell bucket, into a bucket which has or has not teeth as desired. The ordinary clam shell bucket will not dig hard material such as ore, chalk, and other 15 packed products. It is necessary to use an orange peel bucket, or a heavy clam shell bucket, or a clam shell bucket of ordinary weight fitted with teeth. The latter method is in common use on shore, but cannot be 20 used in unloading vessels, as the teeth will damage the bottom if allowed to touch it, so if the teeth are used they must be removed before reaching the bottom, and then replaced before starting the next hatch.

25 There are five or more hatches in the ordinary steamship. Generally teeth are attached by five or six heavy bolts or rivets for each tooth, and there are usually five to nine teeth on the bucket. It is necessary to drill 30 numerous holes near the cutting edge of the scoops where there is great need of strength, and these holes weaken the bucket. To put a set of teeth on may take an hour, and it may take another hour to remove them. This 35 is a serious matter because in unloading vessels time is very essential, and usually a very limited time is allowed for the operation. The bolts used are likely to be bent by the great strain they are subjected to, 40 and the threads are spoiled. It is usually necessary to cut them off to remove them.

The teeth are often bent, and the cutting edge of the bucket is also damaged because the strain on the ends of the teeth cause the 45 latter to act as levers and distort the bucket edge. These reasons make it impractical to use ordinary teeth in ship work. Heavy buckets can be used and are used in connection with shore cranes, but cannot be used 50 with floating cranes. Orange peel buckets cannot be used in ships.

My invention is intended to overcome these difficulties, and to this end I have produced means by which teeth can be very quickly applied or removed from the bucket edges, and 55 in which they are clamped in such a way that

the strain is distributed and the bucket edges in no wise injured. Furthermore, I arrange the teeth so that they can be put in or applied as a unit, provide means for bracing them laterally to prevent displacement, and arrange the device as a whole so that for each tooth a small bolt answers to hold it in place and there is no great strain on this bolt. This will be better understood from 60 the description which follows.

Reference is to be had to the accompanying drawings forming a part of this specification, in which similar reference characters indicate corresponding parts in all the views.

Figure 1 is a side elevation of a common form of clam shell bucket provided with teeth after my idea.

Figure 2 is a broken elevation of the bottom part of one of the scrapers showing 75 the manner of attaching the teeth.

Figure 3 is a cross section on the line 3—3 of Figure 2.

Figure 4 is a section on the line 4—4 of Figure 2, and

Figure 5 is an inside elevation or plan of a portion of the bucket with the attached teeth, the view being diagrammatic to illustrate the means of attachment.

The bucket 10 is shown as the ordinary clam shell bucket, but obviously it can be any hoisting bucket of this general type having opposed scoops which hinge together or which are opened to drop a load. I have shown the meeting edge portions 11 of each bucket scoop provided with teeth 12 which project well beyond the bucket edge as usual, each provided with a shank 12' and the teeth are preferably placed on the outer side of the bucket. On the inner sides opposite each shank is a clamping member or brace 13, which lies flat against the wall of the scoop when it is fastened, and is bent outward near its outer end as shown at 14, the terminal portion being 100 secured to the tooth beyond the bucket edge by rivets 15 or analogous fastenings. The inner end of the member 13 is secured to the inner part of the tooth which lies opposite it by a bolt 16 or analogous fastening, so that it will be seen there is only one hole through the wall of the bucket, and this is well back from the edge. When 105 the nut of the bolt 16 is tightened, the brace 13 is drawn flat against the part 11 of the bucket, and the front edge of the part 11 lies between the shank and the clamping

110

piece. The clamping piece is preferably wider than the tooth, and it will be seen that this arrangement makes a sort of sheath into which the edge of the bucket enters, and the strain is thus distributed and taken up by the two members 12' and 13, the bolt 16 serving simply to hold them in place.

To provide against lateral displacement, I use cross braces 17 which are simply metallic bars lying as shown flat against the wall 11 of the bucket and having upturned end flanges 18 which fit against the shanks 12' but the braces may be otherwise arranged. Bolts 19 or the like pass through adjacent flanges 18 and through the tooth between the flanges, and thus the braces 11 serve as spacing members and also hold the teeth against any lateral displacement. Furthermore it will be observed that this arrangement ties the several teeth together so that by removing the bolts 16, a set of teeth can be removed, and obviously the teeth can as a unit be as easily applied to the bucket.

Various modifications of the particular form of clamping and bracing the teeth will suggest themselves, but I have shown a practical structure which I have used extensively in actual work and which serves the purpose perfectly. I find that the structure effects a great saving in time and is also economical as regards the wear and tear on buckets.

I claim:

- 35 1. As an improved article of manufacture, a hoisting bucket having easily detachable teeth clamped to the edge portion thereof.
- 40 2. As an improved article of manufacture, a hoisting bucket having easily detachable teeth, and means for clamping the teeth as a unit to the edge portion of the bucket.
- 45 3. The combination with a bucket of the

kind described, of a unit comprising a plurality of freely detachable teeth clamped to the edge portion of the bucket, and spacing and bracing members between the teeth.

4. The combination with a bucket, of a unit easily removable therefrom and comprising a plurality of teeth, clamping members connected to the projecting portions of the teeth and arranged so that the bucket wall lies between the teeth and the clamping members, and a through fastening connecting the clamping members, teeth and bucket wall at the free end of said clamping members.

5. An attachment for a bucket comprising a plurality of teeth, each provided with a clamping element secured thereto and adapted to receive the edge of a bucket therebetween.

6. An attachment for a bucket comprising a plurality of connected teeth, each provided with a clamping element secured thereto and adapted to receive and clamp the edge of a bucket therebetween.

7. An attachment for a bucket comprising a plurality of teeth assembled as a unit and each provided with a clamping element adapted to receive and clamp the edge of a bucket therebetween.

8. An attachment for a bucket comprising a plurality of teeth, each provided with an elongated shank, means connecting said shanks to form a unit of said teeth and shanks, and a clamping element secured to each shank and spaced from the latter whereby the edge of a bucket is received between said shanks and said clamping elements, and means for detachably connecting said shanks, clamping elements and the bucket edge.

In testimony whereof, I have signed my name to this specification this 10th day of August, 1925.

FRANCIS H. WEEKS.
